UNITED STATES PATENT OFFICE

2,630,998

SIDE PORTED WELL CASING APPARATUS

Francis Hampton Lee, San Pedro, Calif., assignor
to Baker Oil Tools, Inc., Vernon, Calif., a cor-
poration of California

Application February 24, 1947, Serial No. 730,343

16 Claims. (Cl. 251—8)

1

The present invention relates to side ported apparatus adapted to form part of a casing or liner string positioned in a well bore, and especially designed for controlling flow of fluids through the side ports.

An object of the invention is to provide side ported apparatus connectible in a casing string, whose ports can be positively opened and closed by manipulation of the casing string, and whose external diameter is not substantially greater than the normal outside diameter of the casing string joints.

Another object of the invention is to provide side ported casing apparatus, whose ports can be opened fully without restriction to fluid flow therethrough by manipulation of the casing string, of which the apparatus forms a part, and whose ports can then be closed in response to manipulation of the casing string.

A further object of the invention is to provide side ported apparatus connectible in a casing string, whose ports are closed initially by an external sleeve movable upwardly to port opening position in response to downward movement of the casing string.

This invention has other objects and aspects which will become apparent from a consideration of the embodiment shown in the drawings accompanying and forming part of the present specification. This form will now be described in detail, but it is to be understood that such detailed description is not to be taken in a limited sense, since the scope of the invention is best defined by the claims appended hereto.

Referring to the drawings:

Fig. 1 is a longitudinal view, partly in section and partly in elevation, of an apparatus connected in a casing string, with its parts in the position they occupy when running the apparatus with the casing string in a well bore.

Fig. 2 is a partial longitudinal section of the apparatus, with its parts in side port opening position.

Fig. 3 is a view similar to Fig. 2 with the side ports reclosed.

As illustrated in the drawings, a collar A is connected to upper and lower casing sections B, C of a casing string to hold them in longitudinal spaced relation and to constitute part of the casing string itself. Although specific reference is made in this specification to a casing string, it is to be understood that the invention may also be incorporated in liner and other conduit strings positioned in well bores.

The collar includes an upper inner tubular

member 10 whose upper box end 11 is threaded onto the lower end of the upper casing section B, and a lower outer tubular member 12 whose lower pin end 13 is threaded into the lower casing section C. The upper and lower tubular members 10, 12 are connected together by means of inter-engaging external and internal straight threads 14, 15, which are preferably of right hand. The external threads 14 on the upper member 10 merge into an externally threaded tapered lower portion 16 designed to engage companion internal threads 17 on the lower member 12 extending from and below its internal straight threaded portion 15. The pitch and lead of the tapered threads is the same as that of the straight threads 14, 15.

The lower member 12 is provided with a plurality of circumferentially arranged ports 18 positioned adjacent or through the tapered threaded portion 17, or at some other convenient point therein below the initial location of the lower end 19 of the upper member 10. These ports 18 may be closed initially by the lower portion 20 of an outer sleeve 21 disposed over them and engaging side seals 22 within ring grooves 23 in the lower member 12. The sleeve 21 extends upwardly along the lower member 12 and also along the upper member 10, with its upper end 24 having a slideable sealing engagement with a seal ring 25, such as a round rubber ring, carried within a ring groove 26 in the upper member.

The sleeve 21 is threadedly connected to the upper tubular member 10 by straight internal threads 27 engaging companion external threads 28 on the upper member, disposed above its other straight threaded portion 14. The threaded connection 27, 28 between the upper member and outer sleeve is also preferably of right hand, but having a lead substantially greater than the lead 40 on the lower threaded connection. For example, the lead of the threaded connection 27, 28 between the upper member 10 and sleeve 21 may be twice as great as the straight threaded connection 14, 15 between the upper and lower members 10, 12, and although the thread pitches may be the same, the sleeve connection to the member 10 can be constituted by a double or other multiple thread. The sleeve 21 is adapted for upward longitudinal sliding movement along the lower member 12 upon rotation of the casing string and the upper tubular member 10, being guided in such movement by a longitudinally extending key 29 welded, or otherwise secured, within the sleeve and received within a keyway 30 in the lower member 12.

In the assembly of the apparatus, the sleeve 21 is threaded on the inner tubular member 10 and the latter is threaded within the outer tubular member 12 until its lower end 19 is disposed a substantial distance above the side ports 18. The outer sleeve 21 is then threaded downwardly on the inner member 10 until its internal shoulder 31 abuts the upper end 32 of the lower member 12, which places the lower portion 20 of the sleeve completely over the ports 18 and in sealing engagement with the seal rings 22 disposed on both sides of the ports. The key 23 may now be inserted through the outer sleeve 21 into the keyway 30 in the lower member 12, and the key then welded to the outer sleeve. It is to be noted that the abutting of the sleeve and lower member, and the different threaded connections between the upper member and the lower member and sleeve precludes unscrewing of the two members 10, 12 from each other and prevents separation of the lower casing string from the upper string.

The collar A assembled in the manner just described is connected to the upper and lower casing sections B, C and lowered with the casing string into a well bore to the desired depth. The parts now occupy the position exemplified in Fig. 1, in which the sleeve 21 positively closes the ports 18 against passage of fluids in both directions between the interior and exterior of the apparatus. Fluids may now be circulated down through the casing string and will pass through the collar for exhaustion from the casing string at some lower point therein, as from a shoe (not shown) at its lower end. A charge of cement slurry, or other cementitious material, may now be pumped down the casing string and through the collar A for ejection from the shoe and for upward passage through the annulus around the casing string toward the collar.

After the lower charge of slurry has taken its initial set, and preferably has hardened, the tubular string is rotated from the top of the well bore to effect opening of the ports 18. Since the hardened cement restrains the casing string below the collar A and the lower tubular member 12 attached thereto from rotating, the turning of the upper casing string to the right threads the upper tubular member 10 downwardly within the lower tubular member 12. Since the lower tubular member is prevented from turning by the hardened cement, the outer sleeve 21, connected thereto by the slideable key connection 29, 30 is also prevented from turning. However, the outer sleeve may slide longitudinally of the lower member 12, and such sliding action occurs in an upward direction upon rotation of the upper tubular member 10 to the right, in view of the righthand threaded connection 27, 28 between the outer sleeve 21 and upper member 10.

As indicated above, by way of example, the threads 27, 28 connecting the outer sleeve 21 and upper member 10 have twice the lead of the threads 14, 15 connecting the upper member 10 and the lower member 12. As a result, for each revolution of the upper member, the outer sleeve 21 is moved longitudinally upwardly along the upper member 10 twice the distance that the upper member is moving downwardly within the lower tubular member 12. The net result is an elevation of the sleeve 21 along the lower tubular member 12, as the upper casing string is rotated in a righthand direction a distance equal to the pitch of the threads 14, 15 for each revolution of the upper member 10. The parts are so proportioned and arranged that the rotation of the upper tubular member 10 a predetermined num-

ber of turns moves its lower end 19 downwardly toward the ports 18, but such lower end cannot be disposed across the ports to close them before the lower end of the outer sleeve 21 has moved off the lower seal ring 22 and completely above the ports, in which position the latter are open (see Fig. 2).

Circulating fluid and cement slurry may now be pumped down the casing string for discharge from the collar through its open ports 18. Following the ejection of the required quantity of cement slurry, the upper casing string is again rotated to the right to feed the upper tubular member 10 downwardly within the lower tubular member 12 to engage the tapered threaded portions 16, 17 on the upper and lower members and wedge the lower portion 16 of the upper member 10 firmly into the tapered threaded portion 17 of the lower member 12. In this position the lower portion 16 just referred to is disposed completely across the ports 18 to positively close them against passage of fluids in both directions through the ports. The wedged engagement of the lower portion 16 of the upper member with in the tapered threaded portion 17 of the lower member provides a positive seal, preventing leakage therebetween (see Fig. 3).

For the purpose of insuring that the fluid in the annulus 33 between the sleeve 21 and the upper tubular member 10 is not trapped, and has a path of escape during upward threading of the sleeve along the upper member, a longitudinal bleeder slot or groove 34 may be milled along the external threads 28 in the upper member 10 to a slight distance below its thread roots, allowing the fluid to flow through the threaded connection 27, 28 between the upper member and sleeve 21. Similarly, a bleeder groove 35 may be milled longitudinally along the lower external threads 14 on the upper tubular member 10 to allow the fluid just referred to to continue its downward flowing between the upper and lower members 10, 12 into the interior of the collar.

Since the sleeve 21 is not required for closing the ports 18 after it has been elevated to port opening position, it is unnecessary to maintain the keyed connection between the sleeve and the lower member 12 to prevent its rotation. Accordingly, the keyway or longitudinal groove 30 in the lower member need only be of a limited extent, allowing the key 23 welded to the sleeve 21 to ride upwardly completely out of the groove 30, whereupon its further upward feeding along the lower member 12 need not take place as the upper tubular member 10 is threaded downwardly to wedge its tapered portion 16 into the corresponding tapered portion 17 in the lower member 12, to reclose the ports 18 against passage of fluids in both directions.

The internal diameter through the collar apparatus A is substantially the same as, and, preferably, is no less than, the internal diameter through the casing sections comprising the casing string, in order to avoid introduction of any restricted portions in the casing string. As a result, the lower charge of cement slurry may be pumped through the collar apparatus A through use of the usual casing cementing plug, the latter passing through the collar in the same manner as it moves through the casing sections.

It is further to be noted that the arrangement described enables the outside diameter of the apparatus, which is the outside diameter of the sleeve 21, to be very little greater than the outside diameter of the usual casing couplings or

joints, therefore allowing the apparatus to be employed in well bores whose diameter is relatively close to the outside diameter of the casing couplings.

It is apparent, therefore, that a side ported well casing or conduit apparatus has been provided in which the side ports 18 may be fully opened without the provision of any restrictions to full flow therethrough, simply through manipulation of the casing string from the top of the well bore. Such manipulation, or right-hand rotation, feeds the casing string and the upper tubular member 10 connected thereto in a downward direction in order to take advantage of the force of gravity, but, at the same time, results in upward longitudinal movement of the outer sleeve 21 completely away from closed position over the ports 18, allowing free circulation therethrough. When it is desired to reclose the ports, rotation of the casing string in the same right-hand direction is continued to effect the positive closure across the ports; one which will not leak.

The broad aspects of the invention disclosed herein, particularly those relating to the downward threading of the upper tubular member 10 within the lower tubular member 12 and the wedging of the lower portion 16 of the upper member within the companion tapered portion 17 of the outer member, are described and claimed in my copending application for "Well Cementing Apparatus," executed on February 14, 1947, Serial No. 730,342, filed February 24, 1947.

Having thus described my invention, what I claim and desire to secure by Letters Patent is:

1. Apparatus of the character described, including first and second tubular members telescopically arranged with respect to one another and adapted to form part of a casing string, each of said members having means for attaching such member to a casing section, said first member having a port, means movable with respect to said members and extendible over said port for closing the same, and means providing an interconnection between said port closing means and second member which produces relative shifting of said port closing means and second member in opposite directions, movement of said second member in one direction with respect to said port closing means acting through said interconnection to move said port closing means simultaneously in the opposite direction relative to said first member.

2. Apparatus of the character described, including first and second tubular members telescopically arranged with respect to one another and adapted to form part of a casing string, each of said members having means for attaching such member to a casing section, said first member having a port, said second member being movable with respect to said first member, a sleeve movable with respect to said members and extending over said port to close the same, and means providing an interconnection between said sleeve and second member which produces relative shifting of said sleeve and second member in opposite directions, movement of said second member in one direction with respect to said first member acting through said interconnection to move said sleeve simultaneously in the opposite direction relative to said first member.

3. Apparatus of the character described, including first and second tubular members telescopically arranged with respect to one another

and adapted to form part of a casing string, each of said members having means for attaching such member to a casing section, said first member having a port, a sleeve movable with respect to said members and extending over said port to close the same, means providing an axial connection between said members in order that rotation of said second member will shift said second member longitudinally of said first member, means providing a threaded connection between said sleeve and second member in order that rotation and longitudinal movement of said second member in one direction with respect to said first member will simultaneously move said sleeve longitudinally in the opposite direction along said first member to port opening position, and means engaging said sleeve to restrain its rotation.

4. Apparatus of the character described, including first and second tubular members adapted to form part of a casing string, each of said members having means for attaching such member to a casing section, means providing an axial connection securing said members together in telescopic relation with respect to each other in order that rotation of said second member will shift said second member longitudinally of said first member, said first member having a port, a sleeve movable with respect to said members and extending over said port to close the same, means providing a threaded connection between said sleeve and second member which effects upward movement of said sleeve along said second member to port opening position simultaneously with downward movement of said second member with respect to said first member, and means engaging said sleeve to restrain its rotation.

5. Apparatus of the character described, including first and second tubular members adapted to form part of a casing string, means providing a threaded connection between said members securing them together in telescopic relation with respect to each other, said first member having a port, a sleeve adapted to extend over said port to close the same, and means providing a threaded connection between said sleeve and second member permitting relative rotation between said sleeve and second member and having a different lead than the lead of said threaded connection securing said first and second members together, and means for resisting rotation of said sleeve in order that said sleeve is movable along said first and second members in response to rotation of said second member.

6. Apparatus of the character described, including first and second tubular members adapted to form part of a casing string, means providing a threaded connection between said members securing them together in telescopic relation with respect to each other, said first member having a port, a sleeve slidably keyed to said first member and adapted to extend over said port to close the same, and means providing a threaded connection between said sleeve and second member permitting relative rotation between said sleeve and second member and having a different lead than the lead of said threaded connection securing said first and second members together.

7. An apparatus of the character described, including upper and lower tubular members adapted to form part of a casing string, means providing a righthand threaded connection between said members securing them together in telescopic relation with respect to each other, said

lower member having a port, a sleeve slidably keyed to said lower member and adapted to extend over said port to close the same, and means providing a righthand threaded connection between said sleeve and upper member permitting relative rotation between said sleeve and upper member and having a greater lead than the lead of said threaded connection securing said first and second members together.

8. Apparatus of the character described, including an upper tubular member telescoped within a lower tubular member to provide part of a casing string, means providing a righthand threaded connection between said members, said lower member having a port, a sleeve slidably keyed to said lower member and extending over said port to close the same, and means providing a righthand threaded connection above said first mentioned threaded connection between said sleeve and upper member permitting relative rotation between said sleeve and upper member, said sleeve and upper member threaded connection having a greater lead than the lead of said threaded connection securing said members together.

9. Apparatus of the character described, including first and second tubular members telescopically arranged with respect to one another and adapted to form part of a casing string, each of said members having means for attaching such member to a casing section, said first member having a port, means on the exterior of said first member movable with respect to said members and extendible over said port for closing the same, and means providing an interconnection between said port closing means and second member which produces relative shifting of said port closing means and second member in opposite directions, movement of said second member in one direction with respect to said first member acting through said interconnection to move said port closing means simultaneously in the opposite direction relative to said first member.

10. Apparatus of the character described, including first and second tubular members telescopically arranged with respect to one another and adapted to form part of a casing string, each of said members having means for attaching such member to a casing section, said first member having a port, a sleeve on the exterior of said first member movable with respect to said members and extending over said port to close the same, and means providing an interconnection between said sleeve and second member which produces relative shifting of said sleeve and second member in opposite directions, movement of said second member in one direction with respect to said first member acting through said interconnection to move said sleeve simultaneously in the opposite direction relative to said first member to port opening position.

11. Apparatus of the character described, including first and second tubular members telescopically arranged with respect to one another and adapted to form part of a casing string, each of said members having means for attaching such member to a casing section, said first member having a port, a sleeve on the exterior of said first member movable with respect to said members and extending over said port to close the same, means providing an axial connection between said members in order that rotation of said second member will shift said second member longitudinally of said first member, means providing a threaded connection between said

5 sleeve and second member which effects longitudinal movement of said sleeve to port opening position in a direction opposite to which said second member is moved longitudinally with respect to said first member upon rotation of said second member, and means engaging said sleeve to restrain its rotation.

12. Apparatus of the character described, including first and second tubular members adapted to form part of a casing string, each of said members having means for attaching such member to a casing section, means securing said members together in telescopic relation with respect to each other in order that rotation of said second member will shift said second member longitudinally of said first member, said first member having a port, a sleeve on the exterior of said first member movable with respect to said members and extending over said port to close the same, means providing a threaded connection between said sleeve and second member which effects upward movement of said sleeve to port opening position upon downward movement of said second member with respect to said first member, and means engaging said sleeve to restrain its rotation.

13. Apparatus of the character described, including first and second tubular members adapted to form part of a casing string, each of said members having means for attaching such member to a casing section, means providing a threaded connection between said members securing them together in telescopic relation with respect to each other, said first member having a port, a sleeve movable with respect to said members and adapted to extend over said port to close the same, means providing a threaded connection between said sleeve and second member permitting relative rotation between said sleeve and second member and having a different lead than the lead of said threaded connection securing said first and second members together, and means for relatively rotating said members and sleeve longitudinally along both of said members and said members longitudinally with respect to each other.

14. Apparatus of the character described, including first and second tubular members adapted to form part of a casing string, means providing a threaded connection between said members securing them together in telescopic relation with respect to each other, said first member having a port, a sleeve adapted to extend over said port to close the same, means providing a threaded connection between said sleeve and second member permitting relative rotation between said sleeve and second member and having a different lead than the lead of said threaded connection securing said first and second members together, and means resisting rotation of said sleeve relative to said first member.

15. Apparatus of the character described, including first and second tubular members adapted to form part of a casing string, means providing a threaded connection between said members securing them together in a telescopic relation with respect to each other, said first member having a port, a sleeve adapted to extend over said port to close the same, means providing a threaded connection between said sleeve and second member permitting relative rotation between said sleeve and second member and having a different lead than the lead of said threaded connection securing said first

and second members together, and means on said sleeve engaging said first member to resist rotation of said sleeve with respect to said first member.

16. Apparatus of the character described, including upper and lower tubular members adapted to form part of a casing string, means providing a threaded connection between said members securing them together in telescopic relation with respect to each other, said lower member having a port, a sleeve adapted to extend over said port to close the same, means providing a slideable spline connection between said sleeve and lower member, and means providing a threaded connection between said sleeve and upper member permitting relative rotation between said sleeve and upper member, said last-mentioned threaded connection being of the same hand as said first-mentioned threaded connection and having a greater lead than the

5

lead of said threaded connection securing said first and second members together.
